UNITED STATES PATENT OFFICE.

CHARLES H. PRENTISS, OF CLEVELAND, OHIO, ASSIGNOR OF ONE-HALF
HIS RIGHT TO JOHN P. HUMPHREY, OF SAME PLACE.

IMPROVEMENT IN VAPOR-BURNERS.

Specification forming part of Letters Patent No. **161,635**, dated April 6, 1875; application filed
March 3, 1875.

To all whom it may concern:

Be it known that I, CHARLES H. PRENTISS, of Cleveland, in the county of Cuyahoga and State of Ohio, have invented a Vapor-Burner, of which the following is a specification:

This invention consists in the combination, with the tip *a*, of the flaring and upwardly curved flange *b*, having a recess, *c*, covered by the plate *d*, and also having the opening *e*, as described and claimed.

In the accompanying drawing, Figure 1 is a perspective view. Fig. 2 is a vertical section.

a is the tip, having a broad flaring and upwardly-curved flange, *b*, which is made thick at its junction with the tip, and having a chamber or recess, *c*, in the upper side, which is partly covered by a plate, *d*. The flange *b* is made gradually thinner to the edge, which edge is curved upward, as shown. From the

chamber in the tip is a small opening, *e*, made at such an angle as to direct the current of vapor to the plate *d*, and over an opening, *f*, in the bottom of the chamber *c*.

The operation of this is as follows: The current of vapor issuing across the opening *e*, and in the direction stated, against the plate *d*, mingles with a current of air through said opening *e*, and is thoroughly mixed with the air, and burns with a brilliant flame from the entire edge and points of the flange *b*.

Having described my invention, I claim—

The combination of the tip *a*, the flaring flange *b*, having the recess *c* and the opening *e*, and the plate *d*, as shown and described.

C. H. PRENTISS.
